UNITED STATES PATENT OFFICE.

CHARLES WILLIAM HOPES, OF GLENS FALLS, NEW YORK.

GRATE-BAR.

1,140,158.

Specification of Letters Patent. Patented May 18, 1915.

Application filed July 21, 1914. Serial No. 852,176.

To all whom it may concern:

Be it known that I, CHARLES W. HOPES, a citizen of the United States, and a resident of Glens Falls, in the county of Warren 5 and State of New York, have invented certain new and useful Improvements in Grate-Bars, of which the following is a specification.

My invention relates to furnaces, particularly to the grate-bars employed therein, and the main object is to provide such bars which are designed for use in connection with rice, birdseye, or other fine anthracite or bituminous, low grade, fuel, whereby said fuel 15 is retained upon the grate and an even distribution of air supplied thereto in order to secure proper combustion, said air being diffused throughout all the fuel on the grate.

My invention is fully described in the following specification, of which the accompanying drawings form a part, in which the separate parts are designated by the same reference characters in each of the views, and in which:—

25 Figure 1 is a plan view of a grate-bar constructed in accordance with a present preferred form of embodiment of my invention; Fig. 2 is a section taken on the line 2—2 of Fig. 1; and Fig. 3 is a section 30 taken on the line 3—3 of Fig. 1.

In the drawings forming a part of this application I have shown a main member 4 of relatively thin material, thickened at its ends, as shown at 5, and provided with 35 longitudinally arranged, dependent, side, flanges 6, said member 4 being provided with a plurality of symmetrically arranged bores 7 therethrough, preferably, though not necessarily, in straight rows longitudinally and 40 transversely of the member 4, serving as air passages.

Over each of the bores 7, extending above the upper surface of the member 4, is a projecting cap or boss 8, integral with the member 4 in the form illustrated, and of square formation in plan, the sides thereof being upwardly and inwardly inclined, as shown at 9, and I provide two passages 10 and 11 entirely through the base of said cap or boss 45 and in direct communication with a bore 7, said openings or passages 10 and 11 being at right angles to each other in the form shown, and I provide, as stated, a cap or boss for each bore 7.

50 The said caps or bosses are made of such dimensions as to closely approach each other

at their bases, whereby substantially V-shaped grooves result between adjacent caps or bosses in order to prevent particles of the fuel from passing to and into the ends 60 of the passages 10 and 11, to clog the same and thus prevent the upward and outward passage of air, said grate-bars being particularly designed for use with forced draft, although not necessarily, and it will thus be 65 seen that the air is distributed over the entire fuel area of the grate-bar and proper combustion of the fuel results, and no fuel, other than actual dust, may pass downwardly between the caps or bosses to clog 70 the air passages.

I will, in practice, modify the diameters of the caps, of the grooves therebetween, and of the passages through said caps to 75 adapt the grate bar to different grades of fuel, but make said passages of as large a cross sectional area as is possible in order to secure as great a volume of air through said grate bar as is possible for the particular fuel for which it is designed, and I 80 prefer, as shown, to have the floors of said passages flush with the upper surface of the body member 4 whereby the air fed to the fuel is always thereunder so that a proper combustion results.

85 My invention is very simple in construction, is made of one casting and is, therefore, very durable, assures a thorough distribution of air over the grate area, and is well adapted to the purpose for which it is 90 designed, and it will be seen that I may mount the series of bars, one against another, in order to prevent the possibility of fuel falling therebetween, as is now common 95 where the conventional bars are spaced in order to permit the passage of air.

Having fully described my invention, what I claim as new, and desire to secure by Letters Patent, is:—

1. As an article of manufacture, a grate 100 bar having a main body portion and a raised portion thereover provided with a series of substantially horizontal, parallel, passages therethrough in one direction, and a supplemental series of similar passages 105 therethrough at an angle to the passages of said first named series, said body portion having a vertical bore beneath and joining each intersection of the respective passages of each series, said raised portion being 110 grooved in its upper surface between adjacent passages of each series to intercept

all the passages of the other series, to insure complete diffusion of air passing through said grate bar.

2. As an article of manufacture, a grate bar having a main body portion and a raised portion thereover having a series of grooves in the upper surface thereof in one direction and a supplemental series of similar grooves at an angle to the grooves of said first named series, to form a multiplicity of bosses therebetween, each of said bosses having a plurality of substantially horizontal passages therethrough arranged at an angle to each other, the open ends of the passages of each boss being in register with the open ends of corresponding passages in adjacent bosses, and said main body portion having a vertical bore, beneath each boss, joining the passages through said boss, whereby a thorough diffusion of air results through the fuel over said grate bar.

3. As an article of manufacture, a grate bar comprising a main body portion having a plurality of geometrically arranged vertical bores therethrough, and an integral cap over each bore, each cap consisting of an imperforate plate substantially parallel to said body portion and a plurality of spaced supports of relatively small area for maintaining said plate at a predetermined distance above said body portion and to form air passages therebetween communicating with the respective bore.

4. As an article of manufacture, a grate

bar comprising a main body portion having a plurality of geometrically arranged vertical bores therethrough, and an integral cap over each bore, each cap consisting of an imperforate plate substantially parallel with said body portion and a plurality of spaced supports of relatively small area for maintaining said plate at a predetermined distance above said body portion, the sides of said cap plates and supports being downwardly and outwardly inclined.

5. As an article of manufacture, a grate bar comprising a main body portion having a plurality of geometrically arranged vertical bores therethrough, and an integral cap over each bore, each cap consisting of an imperforate plate substantially parallel with said body portion and a plurality of spaced supports of relatively small area for maintaining said plate at a predetermined distance above said body portion, the corresponding supports of adjacent caps being arranged in groups whereby the air passages formed between the supports of each cap register with the corresponding passages of adjacent caps.

In testimony whereof I have signed my name to this specification in the presence of the subscribing witnesses.

CHARLES WILLIAM HOPES.
